United States Patent Office.

ALONZO HOVINGTON ROWE, OF NEWBURYPORT, MASSACHUSETTS.

Design No. 4,373, dated September 27, 1870.

DESIGN FOR A PUNCH-DRAWER.

The Schedule referred to in these Letters Patent and making part of the same.

To all whom it may concern:

Be it known that I, ALONZO HOVINGTON ROWE, of Newburyport, in the county of Essex and State of Massachusetts, have invented a new and original Design for Punch-Drawer; and I do hereby declare that the following is a full, clear, and exact description thereof, which will enable others skilled in the art to make and use the same, reference being had to the accompanying drawings forming part of this specification, in which—

Figure 1 represents a plan or top view of my new punch-drawer.

Figure 2 is a vertical central section of the same.

Similar letters of reference indicate corresponding parts.

This invention relates to a new drawer for containing the ingredients and implements necessary for the preparation of punch.

The drawer is of quadrangular form, and suitable size. It is provided with plates *a a*, that project from its bottom and form six compartments, *b c d e f*,

and *g*, at the sides and ends of the drawer, as shown.

The compartments *b c*, at one side, are for receiving the knives and spoons respectively that are used in making punch.

The compartments *d e*, at the other side, are for the reception of punch-sticks.

The front compartment *f* is also for spoons, while that in rear, *g*, is for the reception of lemons.

In the middle portion of the drawer there are three apertures, *h i*, and *j*, cut through the bottom *k*, their edges being rebated, as in fig. 2, so that dishes may be suspended from the same.

The dish hung in the aperture *h* is for holding sugar, that in *i* for cut lemons, and that in *j* for wet spoons.

I claim as my invention—

The design for a punch-drawer, as shown.

ALONZO HOVINGTON ROWE.
